CLAIM

The ornamental design for an emery board, as shown.

DESCRIPTION

FIG. 1 is a perspective view of an emery board showing
my new design;

FIG. 2 is a side elevational view thereof, the side oppo-
site being a mirror image of the side shown;

FIG. 3 is a top plan view thereof;

FIG. 4 is a bottom plan view thereof;

FIG. 5 is an end elevational view thereof, seen from the
left of FIG. 4; and

FIG. 6 is an end elevational view thereof, seen from the
right of FIG. 4.
